(57) CLAIM

The ornamental design for exercise steps, as shown and described.

DESCRIPTION

FIG. 1 is a perspective view of my design for exercise steps.
FIG. 2 is a top view thereof.

FIG. 3 is a left side view thereof.

FIG. 4 is a front view thereof.

FIG. 5 is a rear view thereof.

FIG. 6 is a right side view thereof; and,

FIG. 7 is a bottom view thereof.

The broken lines are for the purpose of illustrating portions of the exercise steps that form no part of the claim.
